UNITED STATES PATENT OFFICE

SAMUEL SOLOFF, OF BROOKLYN, NEW YORK

TIE RACK

Application filed December 1, 1928. Serial No. 323,028.

This invention relates to improvements in tie racks and has for its object the provision of a novel form of tie rack which will hold a large number of men's ties or cravats in a minimum of space. A further object of this invention is the provision of a tie rack which may be hung on any convenient wall or other support and from which any individual tie may be withdrawn without disturbing the 10 other ties disposed therein.

Further objects of the invention will be apparent from the specification and drawings in which

Fig. 1 is a perspective view of my improved 15 tie rack, showing the front thereof.

Fig. 2 is a rear view.

Fig. 3 is an elevation of one of the individual bars on which the ties are hung.

Fig. 4 shows a modified form of bar.

20 Fig. 5 is a sectional view along the line 5-5 of Fig. 1.

My improved tie rack has its frame made of two parallel bars A and A' preferably made of flat leather strips. These side 25 pieces are joined together at the top by the lateral metal member B and at the bottom by the lateral metal member C. The top member B has loops D and D' formed therein by which the tie rack is suspended.

30 The bottom member C has joined thereto on the bottom thereof a leather tab E, which is for the purpose of raising the tie rack when filled with ties to remove any individual tie therefrom. The top and bottom 35 members B and C are preferably made of circular metal rods, bent into the desired shape.

The tie holding members are the flat horizontal metal bars F, having the teeth G thereon and integral therewith. The members F are preferably stamped out of flat sheet metal, the ends of the bars F being riveted into the leather side pieces A and A' as shown in Figures 1 and 2. In Figure 4, as shown, 45 an alternative form of tie holding member which is made from a single continuous wire instead of a flat metallic sheet and this form of bar may be used where strict economy in manufacture is necessary. It will be obvious that with this form of tie rack the ties

may be disposed between the spacers G without touching each other and may be removed by lifting the end of the rack by means of the tab E to a horizontal position. Any tie 55 may be easily removed without disturbing any of the others.

In the modification shown in Fig. 4, the bar F is bent to form teeth G.

In use, the device is allowed to hang from the loops D and D', the flexible leather side 60 pieces A and A' being held vertically. When it is desired to remove a necktie, the tab E can be raised until said pieces A and A' are horizontal. The leather side pieces can be rolled up to enable the device to occupy a 65 small space.

I claim:

1. In a tie rack, the combination of flexible leather side supports, a metal rod joining said side supports at the top of said rack, 70 the ends of said rod being turned inwardly to form supporting hooks and a series of rigid horizontal members riveted to said side members at the ends thereof and spacing members located on said horizontal members. 75

2. In a tie rack, the combination of flexible leather side supports, said side supports being joined together at the top and bottom by metal rods having their ends turned inwardly, and a series of horizontal members riveted to said side supports at both ends thereof intermediate the top and bottom of the rack, said horizontal bars having spacing members 80 for the ties integrally formed thereon. 85

3. In a tie rack, the combination of flexible non-metallic side members, metallic bars connecting said side members at the top and bottom of said rack, the ends of said bars passing over the ends of said elastic members and 90 having their own ends turned inwardly, and a series of horizontal bars intermediate the top and bottom of the rack riveted to said side supports and having spacing members located thereon. 95

4. In a tie rack, the combination of flexible non-metallic side members, metallic bars connecting said side members at the top and bottom of said rack, the ends of said bars passing over the ends of said elastic members and 100

having their own ends turned inwardly, and a series of horizontal bars intermediate the top and bottom of the rack riveted to said side supports and having perpendicular spacing members integral therewith and located on said horizontal bars.

5 In testimony whereof I affix my signature.

SAMUEL SOLOFF.
